UNITED STATES PATENT OFFICE.

CHARLES DAVID BONSALL, OF PITTSBURGH, PENNSYLVANIA, ASSIGNOR TO P. H. MURPHY COMPANY, OF NEW KENSINGTON, PENNSYLVANIA, A CORPORATION OF PENNSYLVANIA.

CAR ROOF.

Application filed May 4, 1927. Serial No. 188,669.

This invention relates to single-course insulated car roofs of the type wherein self-supporting roof sheets extend from side to side of the car and are rigidly connected 5 along their adjacent margins by upstanding seams that function as carlines and have members secured therein for suspending the insulating lining beneath said roof sheets.

The principal object of the present invention is to provide a simple and efficient arrangement for supporting the insulating lining, whereby said lining may be quickly and easily placed in position and readily replaced when worn or damaged. Other objects are 15 increased strength, compactness of design and cheapness of manufacture.

The invention consists principally in means hereinafter set forth for securing the insulating lining in place; and it also consists in 20 the parts and in the construction and arrangement of parts hereinafter described and claimed.

In the accompanying drawing, which forms part of this specification and wherein 25 like symbols refer to like parts wherever they occur,

Fig. 1 is a plan view of a portion of an 30 insulated car roof embodying my invention,

Fig. 2 is an enlarged transverse section through one-half of the roof on the line 2-2 in Fig. 1,

Fig. 3 is a vertical cross-section through 35 one of the roof seams on the line 3-3 in Fig. 2,

Fig. 4 is a perspective view of a portion of one of the hanger strips,

Fig. 5 is a perspective view of a modified 40 form of hanger strip; and

Fig. 6 is a view similar to Fig. 3, showing 45 a modified form of the invention.

Referring to the Figures 1 to 4 of the accompanying drawing, my invention is shown in connection with an all-steel riveted-up 50 single-course car roof comprising self-supporting roof sheets 7, which span the car from side plate 8 to side plate 8 and slope downwardly on opposite sides of the ridge to form a pitch or arcuate roof. As shown in the drawing, the side plates 8 are preferably of Z-shaped cross-section and are disposed with their webs horizontal and with their inner flanges extending upwardly. The eaves ends of the roof sheets overhang

the side plates and are supported on and riveted or otherwise rigidly secured to the outwardly extending top flanges of eaves angle members 9, which extend longitudinally of the car and have their depending flanges riveted or otherwise rigidly secured 60 flatwise to the outer faces of the upstanding inner flanges of the said plates. The roof sheets are preferably provided at their eaves ends with depending drip flanges which overhang the outer edges of the eaves angles 9. The roof sheets are provided with upstanding side marginal seam flanges 10 and have their body portions offset upwardly adjacent to said flanges to form raised panels 11 at the side margins of said sheet. 70 As shown in the drawing, the upstanding side marginal seam flanges 10 of the roof sheets are preferably of substantially uniform depth from the ridge to points adjacent to the eaves where they slope downwardly and merge into the plane of the side marginal panels of said sheets at the eaves end thereof.

The roof sheets are arranged on the car side by side; and hanger strips 12 of substantially angular cross-section have one flange disposed between adjacent side seam flanges and the other flange extending beneath the raised side marginal flanges of one sheet and spaced vertically therefrom. Metal seam covers 13 of substantially inverted U-shaped cross-section are placed astraddle adjacent seam flanges of said sheets and the vertical flange of the hanger strip disposed therebetween, and are rigidly secured to said flanges by horizontal rivets 14, thus constituting outside carlines for the roof. The seam covers extend from eaves to eaves of the car and are provided with 85 outstanding base flanges 15 that rest on the raised side marginal panels 11 of the roof sheets and are turned down at the eaves over the depending drip flanges of said sheets. The seam covers are of greater 90 depth at the ridge than at the eaves, each one decreasing in depth to points adjacent to the eaves where it is curved downwardly over the beveled eaves ends of the upstanding seam flanges. The base flanges 15 of 100 the seam covers are wider at the eaves than at the ridge and are secured to the eaves angles and to the underlying panel portions 11 of adjacent roof sheets preferably by

95

100

105

means of rivets. As shown in the drawing, short filler plates 16 are located in the spaces between the upwardly offset or panel portions 11 of the sheets and the outstanding flanges 5 of the eaves angles 9. Running boards 17 extend longitudinally of the car at the ridge and are supported on and secured to the lateral top flanges of angle-shaped running board saddles 18 that are 10 secured to the sides of the seam covers by the securing rivets therefor.

The lateral base flanges of the hanger strips 12 are provided with notches 19 adapted to receive hanger or supporting bolts 19^a 15 for lining supporting members in the form of wooden strips 20 located below the paneled side margins of the roof sheets. The wooden strips 20 extend from ridge to the inner flanges of the side plates and are provided along their top surfaces with a longitudinal groove or channel 21 adapted to receive the base flanges of the hanger strips. The wooden supporting strips are also provided with vertical holes adapted to receive 25 the hanger bolts and have recesses in their under sides adapted to receive nuts 19^b, which are threaded on said bolts and serve to clamp said strips against the under sides of the roof sheets. Located immediately 30 below the roof sheets and extending from ridge to side plate between adjacent supporting strips 20 is an insulating lining comprising sheets or panels 22 of relatively rigid insulating material, such for instance as the 35 material known in the trade as "celotex". Said insulating sheets span the spaces between adjacent supporting strips 20 with their side marginal portions resting in longitudinal recesses 23 provided therefor along 40 the upper side corners of said strips. As shown in the drawing, the recesses which house the nuts 19^b on the lower ends of the hanger bolts 19 are covered by means of separate strips of insulating material 24 which 45 are nailed or otherwise secured to the under side of the wooden supporting strips.

From the foregoing description it is evident that this invention results in a roof which will not sweat or collect moisture on 50 the underside of the roof sheets or on the lining supports or hanger bolts. It also permits the insulating material to be quickly and easily applied to the roof and readily removed and replaced when worn or damaged; it also enables the insulating lining 55 to be clamped tightly against the undersides of the roof sheets and thus support said sheets between seams; and it also permits the hanger bolts to be quickly and easily attached and removed from the base flanges of 60 the hanger strips without disturbing said supports.

In the modification shown in Fig. 5, the lateral base flanges of the angular hanger strip is shown provided with an L-shaped

bolt receiving notches 26 whose inner leg when engaged by the bolt serves to prevent shifting of the bolt transversely of the support.

In the modification of the invention shown in Fig. 6 the sheets of insulation 22^a are spaced below the bodies of the roof sheets and nailed or otherwise secured to the under side of a wooden supporting strip 20^a which is attached to the base flange of the hanger strip in the manner shown in Figs. 1 to 3 and has sufficient vertical thickness to obtain a dead air space between the roof sheets and the insulation.

The invention is not restricted to the precise arrangements of parts shown in the drawing.

What I claim is:

1. A car roof comprising self-supporting roof sheets extending from eaves to eaves of the car and connected along their adjacent margin by seams, hanger members secured to said seams, supporting members detachably secured to said hanger members, and an insulating lining located beneath said roof sheets and supported by said supporting members, said supporting members being adapted to be drawn upwardly towards the sheet to clamp the insulating lining against the under sides thereof.

2. An insulated car roof comprising side plates and self-supporting roof sheets spanning the car from side plate to side plate and rigidly connected along their adjacent margins by seams, angle strips having one flange secured in said seam and the other flange located beneath said roof sheets, supporting strips detachably secured to said angle strips, and an insulating lining located beneath said roof sheets and supported by said supporting strips.

3. An insulated car roof comprising side plates and self-supporting roof sheets spanning the car from side plate to side plate and rigidly connected along their adjacent margins by seams, angle strips having one flange secured in said seam and the other flange located beneath said roof sheets, supporting strips detachably secured to said angle strips, an insulating lining located beneath said roof sheets and supported by said supporting strips, and an insulating lining secured to the under sides of said supporting strips.

4. A car roof comprising side plates and self-supporting roof sheets spanning from side plate to side plate and secured to each other by rigid upstanding seams, hanger strips rigidly secured in said seams and having lateral flanges located beneath said roof sheets, supporting strips bolted to the under sides of the lateral flanges of said hanger strips, and an insulating lining located beneath said roof sheets and supported on said supporting strips.

5. A car roof comprising side plates and self-supporting roof sheets spanning the car from side plate to side plate and rigidly secured to each other by rigid upstanding 5 seams, hanger strips rigidly secured in said seams and having lateral base flanges located beneath said roof sheets, supporting strips bolted to the under sides of the lateral base flanges of said hanger strips, and an insulating lining located beneath said roof sheets and supported by said supporting strips, the lateral base flanges of said hanger strips being provided with notches adapted to receive the securing bolts for 10 said supporting strips. 15
6. A car roof comprising side plates and self-supporting roof sheets supported on said side plates and rigidly secured to each other by rigid upstanding seams, hanger strips rigidly secured in said seams and having lateral base flanges located beneath said roof sheets, supporting strips, bolts for securing said supporting strips to the under sides of the lateral base flanges of said 20 hanger strips, nuts on the lower ends of said bolts, an insulating lining located beneath said roof sheets and supported by said supporting strips, the lateral base flanges of said hanger strips being provided with notches adapted to receive said bolts, and the under sides of said supporting strips being recessed to receive the nuts for said 25 bolts. 30
7. A car roof comprising side plates and self-supporting roof sheets supported on said side plates and rigidly secured to each other by rigid upstanding seams, hanger strips rigidly secured in said seams and hav- 35
- ing lateral base flanges located beneath said roof sheets, supporting strips, bolts for securing said supporting strips to the under sides of the lateral base flanges of said hanger strips, nuts on the lower ends of said bolts, an insulating lining located beneath said roof sheets and supported by said supporting strips, the lateral base flanges of said hanger strips being provided with notches adapted to receive said bolts, the under sides of said supporting strips being recessed to receive the nuts for said bolts, and an insulating lining for covering the under sides of said supporting strips and the nut receiving recesses therein. 40
8. A car roof comprising side plates and self-supporting roof sheets straddling the car from side plate to side plate and rigidly connected by upstanding seams, hanger strips rigidly secured in said seams and having lateral base flanges extending beneath said sheets, supporting strips located below 45 the lateral base flanges of said hanger strips, bolts carried by the base flanges of said hanger strips for detachably securing said supporting strips thereto, said bolts extending through said supporting strips and being provided at their lower ends with nuts, said supporting strips being recessed on their lower sides to receive said nuts and an insulating lining beneath said roof sheets, said lining being secured to the under sides 50 of said supporting strips and covering the nut receiving recesses therein. 55
- Signed at New Kensington, Pennsylvania,
this 29th day of April, 1927.

CHARLES DAVID BONSALL.
